HYDRAULIC PUMP JACK

Armon Jaynes and Thomas W. Bragg,
Gainesville, Tex.

Application December 23, 1941, Serial No. 424,202

1 Claim. (Cl. 60—54.5)

The present invention relates to new and useful improvements in hydraulic pump jacks for wells.

The primary object of the invention is to provide hydraulically operated pumping equipment which is of simple and economical construction and which will be dependable in service requiring a minimum of maintenance.

A further object of the invention is to provide an improved hydraulic pump jack which includes a horizontally disposed cylinder adapted to contain an operating fluid, said cylinder being conveniently arranged at the well and having associated therewith vertically disposed cylinders and pistons operating therein which are connected to the pump rod in the well whereby the well is pumped.

The invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:

Figure 1 is a side elevational view of a hydraulic pump jack embodying the features of the present invention.

Figure 2 is a top plan view thereof.

Figure 3 is an end elevational view.

Referring to the drawing for a more detailed description thereof the improved hydraulic pump jack is generally designated by the reference numeral 5 and includes a pair of horizontally disposed parallel extending members 6 which are positioned on the ground adjacent the well casing 7. The members 6 are united by means of transverse beams 8 and 9, respectively, connected by any desired means. Members 6 adjacent the well casing 7, and at their ends, are formed with enlarged portions 10 through which bars 11 are slidably mounted. Connector bars 12 and 13, respectively, are attached to each end of the slide bars 11 the same being held thereon by means of nuts, or the like, 14. As best shown in Figure 2 of the drawing, the slide bars 11 are mounted directly above the members 6 and are held spaced therefrom by means of the connector bar 12. Attached to the forward connector bar 13 is a pull rod 15 leading to a source of power, not shown, and representing actuating means whereby reciprocation may be imparted to the slide bars 11 for actuating the plunger 16 within

the horizontally disposed cylinder 17, to be hereinafter more fully described.

The cylinder 17 is disposed substantially centrally of the members 6 and is held on one end by means of the transverse beam 9, said cylinder adapted to contain a quantity of fluid such as oil, or the like. The other end of the cylinder 17 is connected with a substantially V-shaped head 18 formed with a conduit 19 in communication with said cylinder. The head 18 is formed with end blocks 20 which extend beneath enlarged portions 10 inwardly from the ends of the side members 6 and are attached thereto.

Vertically disposed cylinders 21 and 22 are mounted on the head 18 and are in direct communication with the conduit 19. Pistons 23 and 24 are mounted within the cylinders 21 and 22 the same being connected by means of a cross bar 25 held on said pistons by means of nuts, or the like, 26. The polish rod 27 which is actuated for pumping the well 7 is connected to the cross bar 25, as indicated at 28, whereby movement of the pistons 23 and 24 will actuate the polish rod 27 through the medium of the cross bar 25.

In the operation of the device, power is applied to the pull rod 15 for reciprocating the slide bars 11. Since the plunger 16 is attached to the connector bar 12, as indicated at 29, said plunger will reciprocate within the piston 17 to force the fluid through the conduit 19 into the vertically disposed cylinders 21 and 22. The force of the fluid will raise the pistons 23 and 24 and the cross bar 25 for actuating the polish rod 27. As best shown in Figures 2 and 3 of the drawing, the shape of the head 18 permits it to surround the well casing 7 and the entire pump jack 5 can be moved to various positions within the radius of the horizontally disposed cylinder 17. Due to the formation of the pump jack, the head will also fit around the well casing 7 in such a manner as to arrange the upright cylinders 21 and 22 at diametrically opposite sides of the polish rod 27.

Also it will be understood, of course, by those skilled in the art that variations in the hereinabove-described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect

the spirit of the invention nor exceed the scope thereof as expressed in the appended claim.

What is claimed is:

In a hydraulic jack designed to fit about a well casing and be moved to various operative positions in a circle about the well casing, a horizontal movable supporting frame, a plurality of associated pumping parts carried by and arranged for horizontal movement on the frame and including horizontal slide bars journaled on the frame and connected with a source of power, a horizontal plunger on the slide bars, a horizontal cylinder carried by the frame within which the plunger operates, said frame having

spaced side members the ends of the side members adjacent the cylinder having enlarged portions, a Y-shaped head on the cylinder formed with blocks attached to the side members of the frame beneath the enlarged portions and designed to go about a well casing, said head having passages leading to its ends from the cylinder, and vertically positioned cylinders on the ends of the heads communicating with the passages and having pistons connected to the ends of a cross-bar of a polish rod extending into a well casing.

ARMON JAYNES.

THOMAS W. BRAGG.
